[57] **CLAIM**

The ornamental design for combined vehicle model and micro sound chip for a cap, as shown and described.

DESCRIPTION

FIG. 1 is a top plan view of a combined vehicle model and micro sound chip for a cap showing my new design; FIG. 2 is a front elevational view thereof; FIG. 3 is a right end elevational view thereof; and, FIG. 4 is a left end elevational view thereof.

The broken line showing of the cap in all views is for illustrative purposes only and forms no part of the claimed design.
